UNITED STATES PATENT OFFICE.

ARNOLD NACKE, OF PHILADELPHIA, PENNSYLVANIA, ASSIGNOR TO LEDIG & HERRLEIN, OF SAME PLACE.

SCREW-CUTTING TOOL.

SPECIFICATION forming part of Letters Patent No. 279,495, dated June 12, 1883.

Application filed November 21, 1882. (No model.)

To all whom it may concern:

Be it known that I, ARNOLD NACKE, of Philadelphia, in the county of Philadelphia and State of Pennsylvania, have invented certain Improvements in Screw-Cutting Tools, of which the following is a specification.

This invention relates to a screw cutting or frasing tool wherein a series of radially moving or expanding cutters are applied to pivoted arms mounted in a supporting-body, and connected with devices whereby they may be operated, and with means whereby they are automatically moved to open the cutters whenever the screw-thread has attained a predetermined length.

The improvements consist in the various details of construction relating to the tool, which will be hereinafter described in detail, and to a supplemental gage adapted to effect the simultaneous and uniform adjustment of the cutters in order to adapt the tool for threading screws of different diameters.

Referring to the accompanying drawings, Figure 1 is a longitudinal central section of my improved tool. Fig. 2 is a cross-section on the line $x-x$. Fig. 3 is an elevation of the body portion of the tool, one-half being represented in section. Fig. 4 is an end view of the same. Fig. 5 is an elevation, one-half in section, of the central portion of the body. Fig. 6 is an elevation, one-half in section, of the central device whereby the cutter-supporting arms or levers are locked and released. Fig. 7 is a perspective of one of the cutter-supporting arms. Fig. 8 is a rear end view of the complete tool. Fig. 9 is a side elevation of the rear end portion. Fig. 10 is a face view of the device for adjusting the cutters concentrically. Fig. 11 is a view illustrating the action of the jaw-operating lever and adjacent parts.

Referring to the drawings, A represents the main body portion of the tool, made of substantially cylindrical form, with a series (usually four) of longitudinal slots, a, therein to receive the levers B, the forward ends of which are provided each with a cutting or frasing tool, C. Each lever B is secured in the body A, at a central point, by means of a transverse pivot, b, whereby the series of levers are permitted to move to and from each other at their forward ends in order to close the cutters inward

toward the center in position to operate upon the blank to be threaded, or to admit of their being separated when the finished screw is to be released. Each lever B is acted upon by a flat spring, D, secured to the body, as shown in Fig. 1, tending to throw the levers and cutters apart at the forward end when released.

For the purpose of operating the levers I mount centrally within the body A a secondary body-section, E, upon which the body A is free to slide endwise, as shown in Fig. 5. The forward end of the inner section, E, is provided with an angular neck, e, which fits within a corresponding angular opening, d, in the outside body, A, whereby the two body-sections A and E are compelled to rotate in unison, although one is free to slide endwise in respect to the other. Within the rear end of each cutter-supporting lever B, I pivot one end of a link, G, the opposite end of which is pivoted in a slot in the central body, E, in the position indicated in the drawings. When, therefore, the outer body-section, A, is moved forward upon the inner section, E, the links are caused to assume an upright position, thereby by operating the levers B in such manner as to throw the cutters inward to operative position. A backward movement of the body A, on the contrary, operates the levers in such manner as to separate the cutters from each other. This movement of the body-sections A and E—one in relation to the other—is effected by means which will now be explained. The inner section, E, has its end enlarged to a diameter equal to that of the section A, and is provided with a peripheral groove, e, wherein an encircling-ring, H, is loosely mounted. In like manner the rear end of the section A is provided with a circumferential groove containing a loose ring, I. The two rings are connected and prevented from turning in relation to each other by means of an encircling band or hoop, J, having on its inner surface, in the direction of its axis, ribs j, which are seated loosely in corresponding grooves in the two rings. This connection, while preventing the rings from rotating in relation to each other, as before stated, admits of the ring I moving laterally with the outer body-section, A, to and from the ring H.

To the opposite sides of the ring H, I pivot

the arms of a forked lever, K, the motion of which in a backward direction is limited by means of stop-pins *i*, screwed into the ring in position to encounter the end of the lever, as 5 shown.

To each end of the lever, on the forward side, I pivot at *n* a cam-lever, L, bearing at its free end against the adjacent pin *i*, and upon the exterior of the ring I, I mount two rollers, N. 10 On moving the hand-lever to the right, the levers L, resting at their forward ends upon the pins *i* as fulcrums, have their rear ends carried to the right by the hand-lever, whereby they are caused to act against the rollers N, 15 thereby forcing the ring I away from the ring H and moving the body-sections A forward upon the inner section, E, so as to close the cutters in the manner before explained. Screws M, inserted through the rear ends of the cam-levers L, encounter the hand-lever and serve 20 to limit motion of said levers L in relation to the lever K. The forward ends of the levers L, encountering in turn the studs *i*, serve to limit the motion of the hand-lever in that direction by which the jaws are closed.

By adjusting the screw M the forward motion of the hand-lever may be regulated with great accuracy, and thus the cutters prevented from closing so near each other as to reduce 30 the diameter of the screw below the limit desired.

For the purpose of throwing the lever backward when relieved from pressure, a spiral spring, O, is applied thereto, and arranged to 35 bear at one end against the ring H or a stud thereon.

For the purpose of giving direct and solid support to the cutter-carrying levers B during the action of the cutters, I mount centrally 40 within the inner body-section, E, a longitudinally-sliding tube, P, having its rear end enlarged and provided with forwardly-extending arms *n'*, which extend through openings in the body A in position to engage beneath the rear 45 ends of the respective levers B.

Spiral springs Q, seated in the rear end of the inner section, E, are secured at one end to said section and at the opposite end to the rear end of the sliding tube P. Whenever, therefore, the rear ends of the levers are moved apart 50 to throw the cutters inward, the tube P is moved forward by the action of the spiral springs, and the arms *n'* caused to rest beneath the ends of the levers B, as shown in Fig. 1, thus holding 55 the levers solidly in their operative positions.

The central tube, P, may be extended forward between the levers B in position to be encountered by the end of the screw or other object threaded by the tool whenever the same 60 has reached a predetermined length.

By means of the screw the tube P will be forced backward and the arms *n'* removed from beneath the levers B, whereupon the latter will be immediately actuated by means of the 65 springs D, and their forward ends thrown apart, so as to separate the cutters.

For the purpose of adjusting the device for

automatically producing screws of greater or less length, as required, the central tube, P, is provided with a central longitudinal screw, R, 70 the forward end of which has a loose swiveling head, S.

By adjusting the screw forward and backward, and thereby virtually lengthening or shortening the tube P, the automatic release 75 of the cutters may be effected whenever the screw has entered a given distance beyond the cutters.

The forward ends of the levers B are split or divided, as shown, to embrace the cutters, and 80 are provided with transverse screws T, where by the divided ends may be compressed upon the cutters.

By adjusting the cutters C inward and outward from the ends of the levers the tool may 85 be adapted for the cutting of screws of different diameters.

To secure the proper action of the tool it is necessary that the several cutters shall be adjusted with their inner ends at exactly the 90 same distance apart from the axis of rotation. To secure this adjustment with readiness and certainty, I make use of a plate, U, such as represented in Fig. 10, provided with concentric slots *p* and eccentric slots *q*.

Each of the levers B is provided at its ends with a fixed stud, *r*, and each of the cutters C provided with a similar stud, *s*.

In making use of the adjusting-plate U the cutters are first released, after which the plate 100 is applied, as indicated by dotted lines in Fig. 1, the concentric slots *p* receiving the studs upon the ends of the arms, and being compelled thereby to revolve about a center coincident with that of the tool, while the eccentric slots 105 *q* receive the studs upon the cutters, so that as the plate is turned the eccentric slots will move the several cutters inward or outward to precisely the same extent. The cutters are secured in position while thus held to the plate, 110 after which the plate is removed.

While it is preferred to make use of the studs and slots as a means of holding the plate in position, it is manifest that any other suitable guide which will cause the plate to revolve 115 about the central axis of the tube may be substituted. A simple means to this end will be an overhanging flange to encircle the outer ends of the cutter-supporting arms.

Having thus described my invention, what I 120 claim is—

1. The combination of the body-sections A and E, arranged to slide one upon the other, the cutter-supporting levers, the links, the loose rings mounted one in each of the body-sections, and means, substantially as described, connecting said rings with each other, whereby they may be moved to and from each other for the purpose of moving one body-section in relation to the other to effect the opening and 130 closing of the cutters.

2. In combination with the body-sections A and E, the cutter-supporting levers B, and the central slide provided with arms adapted

to engage with the rear ends of the cutter-supporting levers, substantially as shown.

3. In combination with the body-sections, sliding one upon the other, the cutter-supporting levers, the links, and the slide for locking the levers, provided with an adjustable or extensible device, R, at its forward end, whereby the tool may be adjusted for automatically determining the length of screws produced.

10 4. In a screw-cutting tool, the combination of the external body, A, provided with longitudinal slots, the cutter-supporting levers mounted in said slots, and the internal body E, provided with an angular neck or portion 15 seated in a corresponding cavity in the body A, and links connecting the levers with the internal body-section, substantially as described.

5. In a screw-cutting tool, the combination of the longitudinal levers provided with cutters at their forward ends, means, substantially as described, for moving said levers on their pivots, and the spring-actuated locking-slide adapted to engage with and hold the rear end 25 of the levers in an operative position, whereby the automatic locking of the levers is effected.

6. In combination with the two body-sections sliding one in relation to the other; the links, and the cutter-supporting levers, the central slide, P, provided with locking-arms to 30 hold the levers, and a spring, applied substantially as shown, to urge the locking-slide forward.

7. The combination of the body-sections, the cutter-supporting levers, means, substantially as described, for operating said levers with the rings applied to the body-sections, and a hand-lever and connecting devices, substantially as shown, adapted to move one of said rings laterally with respect to the other.

40 8. In combination with the two rings applied

to the body-section, substantially as and for the purpose described, the hand-lever, the stop-pins applied to the rings, and the arms or cams adjustably attached to the ends of the hand-lever, substantially as described.

45 9. In combination with the two rings applied as and for the purpose described, the hand-lever, the stop-pins, the pivoted cams or arms applied to the ends of the hand-lever, and the adjusting-screws whereby the position 50 of said arms in respect to the hand-lever may be varied.

10. Jointly with the cutter-supports and the cutters C, adjustably mounted therein, a plate, U, constructed and arranged to operate in connection with the cutter-supports for the purpose of effecting the uniform adjustment of the cutters, substantially as described and shown.

55 11. Jointly with the cutter-supports B, having studs r, and adjustable cutters C, provided with studs s, the adjusting-plate U, provided with concentric slots p and eccentric slots q to act upon the respective cutters and effect their uniform adjustment.

60 12. Jointly with a screw-cutting tool having a series of cutters adjustable to and from the center, a detachable plate adapted to revolve concentrically upon the cutters, said plate being provided with eccentric bearings 70 to act upon the respective cutters and effect their uniform adjustment, substantially as described.
